EARL G. PORTS, OF WOODSIDE, NEW YORK, AND HERMAN P. MILLER, JR., OF EAST ORANGE, NEW JERSEY, ASSIGNEES TO INTERNATIONAL COMMUNICATIONS LABORATORIES, INC., OF NEW YORK, N. Y., A CORPORATION OF NEW YORK

TUNING COIL

Application filed February 27, 1931. Serial No. 518,750.

Our invention relates to electrical coils and particularly to coils for use in connection with the circuits of radio apparatus.

An object of our invention is to provide 5 a mounting upon which the turns of a coil can be disposed and which is inexpensive, simple, easily constructed, strong, durable and capable of permitting the coil thereon to be readily connected in operative relation.

10 The mounting proper comprises two end pieces to which are attached bars for supporting the coil or coils. The bars are attached to the end pieces in such a manner as to form a rigid cage-like structure.

15 The main portion of the coil which contains the greater number of turns is arranged to encircle the mounting so suitable taps or leads can be readily attached thereto.

20 Another portion of the coil is arranged within the mounting in order that the turns or spirals may be engaged by a conductor arm mounted upon a central shaft which passes through the mounting.

25 Another object of our invention is the arrangement whereby the conductor arm engages the inner coil within the mounting during the rotation of the shaft.

Other features of our invention will be 30 pointed out in the description to follow.

Referring to the drawings:

Figure 1 is a section on the line 1—1 through Figure 2 of one design of the coil according to our invention.

35 Figure 2 is a plan view seen from the bottom of the construction in Figure 1.

Figure 3 is an end view of another type of coil according to our invention.

Figure 4 is a bottom view of what appears 40 in Figure 3.

Figure 5 shows a detail of certain parts shown to right of Figures 3 and 4.

Figure 6 is an end view of another form 45 of our invention, and

Figure 7 is a plan or a side view seen from beneath the coil shown in Figure 6.

The same numerals identify the same parts throughout.

50 Referring first to Figures 1 and 2, we show a supporting framework having substantial-

ly the shape of a cylindrical cage and comprising longitudinal bars 1 attached at their extremities to ends 2. The bars 1 and ends 2 are of insulation, the ends 2 have preferably the form of cylindrical discs and the bars 1 being engaged by the turns of the coil indicated at 3. The movable contact arrangement provides for fine adjustment of inductance value when the main portion of inductance or coil 3 is selected by placing 55 clips at desired positions on the coil 3. Each of the bars 1 consists of a deeper portion 5 somewhat longer than one-half the length of the bar 1 and another portion 5a of less transverse depth, and is of least depth 60 at its extremities which are affixed to the ends 2. The edges of these bars are notched to receive the turns 3, the larger part of the turns 3 being wound around the outside of the bars 1 and a selected number of turns 65 being disposed inside of the bars 1 entering notches on the inner edges of these bars so that they can co-operate with the contact 4.

The extremities of the bars fit into recesses 7 in the circumferential edges of the ends 2 75 and are secured in any suitable manner as by means of pins 8 driven to suitable holes made by boring the extremities of bars 1 and ends 2 as shown in Figures 3, 4, 6 and 7. The extremities of the coil are secured to 80 the ends 2 by means of bolts 9.

To secure a supporting framework of this construction in position, we provide a bracket 10 with openings for screws 11 which serve as terminal leads. The bracket 10 has 85 the two arms 70 attached to the main portion by the angle piece 12 by means of the screws 71. The two arms 70 are attached to the ends by the screws 72.

The ends 2 have openings to provide bearings for the shaft 13 which rotates the contact or conductor arm 4. This shaft has a metallic section 14 at one extremity and a similar metallic section 15 at the other extremity, these two sections being supported in the ends 2 and connected by an intermediate section 16 of insulation. Couplings 17 and 18 connect the sections 16 to the sections 14 and 15. The coupling 18 is preferably metallic and on the other extremity 90 95 100

of the portion 15 is a metal collar 19 which rotates in contact with a conducting brush 20 secured by a block 21 to the adjacent end 2.

5 At 22 is a yoke, the arms of which are pivotally connected to the sleeve 18 by a pin 23. This yoke is of metal and contact between it and the coupling 18 is secured by a short length of flexible conductor 24. To 10 the outer end of the yoke are attached blades 25 and 26 of conducting material. The blade 25 is fairly stiff while 26 is flexible. One of these blades rests upon one face of the turns 3 of the coil and the other presses 15 against the other face of the same turn. The turns are in the form of flat bands which project inside beyond the edges of bars 5a. The contact arm 4 can thus not only rotate when the shaft 13 is turning, 20 but it can also swing on its pivot 23 and thus move over the entire length of the limited number of turns 3 as are attached to the inner edges of the bars 1. One terminal of the circuit is connected to the brush 25 25 and the other to the screw 9 at the opposite end of the coil. The number of turns can, of course, be varied by the addition or subtraction of all the turns 3 engaging in the inner edges of the bars 5a, or less than 30 all according to the number desired. Any suitable means for turning the shaft 13 can of course be employed.

We mount upon the shaft 13 outside of the framework a pinion 27 which meshes 35 with the gear 28 mounted on a bracket 29 by means of screw 32 which passes through ends 2 and is held by a nut as shown. Notches 31 are provided as a means of adjusting the angle of rotation of the gear. 40 Adjustment is accomplished by filing the notches to the depth required. Otherwise, bracket 29 would have to be cut to a precise width. The gear 28 rotates only far enough to carry the stop 30 from one of the notches 45 31 in bracket 29 into the other. Since the gear 28 is larger than the gear 27, the contact arm 4 can therefore make several revolutions, but with the diameters of the gears 27 and 28 properly chosen the arm is limited 50 in its movement so that it can only travel from one end to the other over the turns 3 which are on the inside of the supporting framework of the coils.

55 This kind of framework can be made strong and durable and answers very well for the purpose of supporting a coil for radio work, such as the loading coil of an antenna. By rotating the arm 13 the number of turns 3 and the total inductance of 60 the coil can be adjusted as required.

In Figures 3, 4 and 5 a similar design of supporting framework is shown with all the turns 3 of a coil wound around the outside of the bars 1. These bars have the same shape as before except that they are

of uniform depth between the ends 2 and their extremities are reduced to engage the recesses 7 of these ends. Two of these bars, however, are of greater thickness and are disposed in opposite ends of a diameter as 70 at 1a in Figures 3 and 4 to provide bearings for a hollow cylinder 33 of insulating material which is mounted on the inside of the framework to carry a coil in adjustable inductive relation to the coil, comprising the 75 turns 3, which is fixed. By shifting the position of the tubular member 33, the coupling between the inside and outside coils can, of course, be varied.

To mount the tubular member 33, we use 80 journals 34 rotatably supported in the bars 1a and rigidly attached to opposite sides of the tubular member 33. These journals or trunnions 34 are of metal and turn in sleeves 35 of insulating material inserted through bores in bars 1a and held by pins 36 which prevent these sleeves 35 from turning. The sleeves project beyond the outside faces of the bars 1a and extend into bores provided in blocks of insulation 37. These blocks have 85 apertures to align with similar apparatus in the bars 1a to receive fibre bolts 38 carrying nuts 39 which prevent displacement of the blocks 37. The block 37 at the left in Figures 3 and 5 has a shoulder made by 90 attaching a piece of metal 40, and the associated trunnion 34 projects through the block 37 and carries on its outer end a head 41 which enables it to be secured by a screw 100 or the like to a flexible conductor 42. Screws 43 are employed to attach the other extremity of conductor 42 to the part 40 and to secure the metal block 40 and block 37 together. On the opposite side of the tubular member 33 the trunnion 34 carries on its outer extremity a head 44, affixed by a screw or any other suitable means. This head is encircled by a flange 45 and it carries in its extremity a notch or kerf 46 to fit the end of a screw-driver or other tool so that the position of the tubular member 33 can be varied. We also attach to the adjacent face of the block 37 a block 47 of suitable material, preferably metal, this block 105 having a slot therein as shown at 48 to receive the edge of the flange 45, screws 49 securing the block 47 to the block 37; block 47 having bores for these screws of larger diameter from one face insofar as the slot 48 is placed so that the heads of the screws 49 may be well within the block 47. Another screw 51 passes in through block 47, engaging a threaded portion of the block 47 at its inner end, and so allows clamping of flange 45 to retain rotatable elements in any desired position. A conductor 52 is secured by a screw 53 to the block 47 and connected with the adjacent trunnion 34 by inserting its opposite extremity into a notch in the head 44 as shown at 54 in Figure 5. The 110 115 120 125 130

collar or flange 45 may have projecting studs 55 to prevent rotation of the rotatable portion more than a desired amount by striking against block 47 at either extremity of 5 rotation. This conductor is flexible and permits rotation of the adjacent trunnion 34 when member 33 is to be turned. The turns of the coil on this member are shown at 56 and this coil is connected at its opposite extremities to the trunnions 34 which are affixed to the member 33 in any feasible manner. This construction serves very well in coupling an antenna to the co-operating circuits of a sending or receiving device, the 15 coil on the member 33 preferably being directly in the antenna circuit. Obviously, this device can be used for other circuits also.

In Figures 6 and 7 the supporting framework consists of bars 1 all of the same shape attached to ends 2; with a coil comprising turns 3 wound around the outside of the framework; and with another coil inside the framework; the coil inside being preferably fixed and the two coils co-axial. 25 The inside coil is wound upon a tubular member 57, one end of which has a cross-bar 58 and the other a cross-bar 59. These two cross-bars can be of pieces of insulation of the same material as the member 57 fitted 30 inside the ends of the member 57 and secured by pins 8. The ends 2 may be bridged by cross-bars 60 and 61 secured by screws 62. The bar 58 may be affixed to the bar 60 and the bar 59 to the bar 61. The bars 35 60 and 61 may be employed to attach the entire construction to any suitable device such as the inside of a casing or cabinet wherein the coil is to be supported for use. At 40 the extremities of the outside coil are connected to the operating circuit and the terminals of the inside coil are shown at 63 and 64. These terminals have the form of bolts which constitute convenient binding posts for the circuit conductors.

45 This construction also provides a strong durable yet easily built framework and the

inside and the outside coils can conveniently be employed to couple the grid and plate circuits of a vacuum tube together, or they may be utilized in other circuits, as will be readily understood.

70

What I claim is:

1. A supporting framework for an electrical coil comprising ends connected by longitudinal bars, a spiral conductor having its turns fitting into notches in said bars, some of said turns encircling the bars and the remaining turns being surrounded thereby and disposed in notches on the inner edges of said bars, a central shaft supported in bearings in said ends, a conductor arm pivotally connected to said shaft in contact with said last named turns, means for limiting the rotary movement of said shaft, wherein the shaft comprises metallic extremities connected by an insulating section, the conductor arm comprising blades which engage different portions of the conductor, and the means for limiting the rotary movement of the shaft comprises gears one of which has a projection, and a bracket attached to the framework to serve as a stop for said projection.

75

2. A supporting framework for an electrical coil comprising ends connected by longitudinal bars, a spiral conductor having its turns fitting into notches in said bars, some of said turns encircling the bars and the remaining turns being surrounded thereby and disposed in notches on the inner edges of said bars, a central shaft supported in bearings in said ends, a conductor arm pivotally connected to said shaft in contact with said last named turns, means for limiting the rotary movement of said shaft, and means for mounting the framework including a bracket attached to said ends and having fastening members which also serve as terminal leads for the coils.
